INVENTOR
H. W. ARNOLD

By *Wright & Chase*

ATTYS.

UNITED STATES PATENT OFFICE.

HENRY W. ARNOLD, OF SACRAMENTO, CALIFORNIA, ASSIGNOR TO OLD MOTHER HUBBARD'S GROCERY CUPBOARD CORPORATION, OF SAN FRANCISCO, CALIFORNIA, A CORPORATION OF CALIFORNIA.

DISPLAY AND SELLING APPARATUS.

Application filed April 13, 1920. Serial No. 373,583.

To all whom it may concern:

Be it known that I, HENRY W. ARNOLD, a citizen of the United States, residing at Sacramento, in the county of Sacramento and State of California, have invented new and useful Improvements in Display and Selling Apparatus, of which the following is a specification.

This invention relates to apparatus for displaying and dispensing packages, particularly canned goods, and other packaged food products or commodities which are sold in uniform and standard sizes.

It is believed that the sale of food products of the character described will be augmented, effective advertising will be secured, and that a great convenience to the public will be provided by the establishment of "food stations" at points out of the business centres and shopping districts of large towns and cities and also at remote points along state highways, roads, and the like.

These stations put up after the popular fashion of gasoline service stations and constructed in a novel, attractive and inexpensive manner, will serve not only to effectively display and advertise the goods to be sold, but will prove convenient to the consumers.

Accordingly, it is the primary object of this invention to make commercially practicable the establishing of food stations and I do this by providing comparatively small and inexpensive apparatus which may be quickly assembled to provide a compact store unit arranged and constructed so as to facilitate the display, the handling, storing, and vending of the goods to be sold.

A further object of the invention is to provide apparatus of the character described constructed so that when disassembled, or even assembled, may be easily transported by rail, motor vehicle, or otherwise, and quickly set up in less than, for example, an hour, so as to provide a complete, compact, attractive store and display unit, adapted to house an attendant and dispense goods in a novel and time-saving manner.

A still further object is to provide apparatus of the character defined, in which only one commodity of each kind will be displayed at the same time and in which the various commodities will be stored in a compact,

convenient, manner, and in which they may be conveniently moved into display position in succession after previous ones of the same kind have been sold.

The invention possesses other advantages and features, some of which, with the foregoing will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form, since the invention as expressed in the claim may be embodied in a plurality of forms.

Referring to the drawings:

Figure 1 is a front elevation of the apparatus of this invention, showing a part thereof broken away.

Figure 2 is a horizontal sectional view of the apparatus.

Figure 3 is a vertical sectional view of the apparatus.

Figure 4 is a top plan view of the dispensing apparatus for flat packages.

Figure 5 is a longitudinal sectional view taken on the line 5—5 of Figure 4, showing the dispensing apparatus in normal position.

Figure 6 is a similar longitudinal sectional view showing the dispensing apparatus in operative position.

Figure 7 is a top plan view of dispensing apparatus for round objects.

Figure 8 is a longitudinal sectional view taken on the line 8—8 of Figure 7.

Figure 9 is a sectional view taken on line 9—9 of Figure 4.

In carrying out my invention, I provide an enclosed structure of wood or any other suitable material, made up of one or more sections as desired, and divided into two compartments, one compartment being for a clerk or attendant and is of just sufficient size to permit one person to operate freely therein. This compartment is provided in part with transparent front walls. The other compartment contains a series of sub-compartments opening into the attendant's compartment and adapted to contain goods and commodities so as to display the goods, this being possible by provision of the transparent front wall. The attendant's com-

partment houses an extensible cabinet or container, the outer wall of which acts as a closure for an opening in the transparent front wall, through which opening the cabinet is 5 extended to permit the upper wall thereof to serve as a counter, there being windows opening above the said opening.

The present embodiment of the invention 10 is made up of a preferably rectilinear structure comprising a front wall 1, side walls 2, rear walls 3, a top wall or roof 4 and a floor 5, all suitably joined to form a compact weather proof enclosure. This structure is 15 divided into compartments 6 and 7, for an operator and for storing and displaying goods, respectively. Preferably the compartments comprise separate units of the structure, joined to one another to provide the complete structure. With this arrangement, the attendant's compartment is wider 20 than the food compartment and has a rear wall 8 joined to the side wall 2 of the latter compartment. By making the structure in two similar units, the assembling and transportation thereof is facilitated.

The front wall 1 has doors 9 and 10 thereon 25 on opposite sides, the upper parts of the doors being formed of glass panes, as in a "French" door, whereas the lower parts may 30 be panelled in the ordinary manner.

The display and storage compartment may 35 be filled from the attendant's compartment or from the back, in the latter case through doorways closed by suitable back doors. In 40 the food compartment is the means for facilitating the displaying and handling of round or cylindrical packages, also the similar means for flat or flat-sided packages. These means are constructed and arranged to 45 provide for convenience of reaching, handling, displaying, and dispensing the goods to be sold.

An opening 12 is provided in the front 50 wall 1 approximately in the center thereof, and receives a combined cabinet and counter member 13. This member 13 may be made in the form of an ice-box or a cabinet, as desired, and is rectilinear in cross section, the outer wall 14 thereof serving for a closure 55 for the opening 12 when said cabinet is disposed within the compartment 6, as shown in dotted lines in Figure 3 of the drawings. There are provided rollers 15 on the lower side of the cabinet 13 so as to provide 60 for rolling said cabinet into, and out of, position. When the cabinet is extended, as shown in Figure 3, the top wall 16 thereof serves as a counter over which the goods are sold. To provide for access to the counter, outwardly opening windows 18 are hinged, as at 19, to the front wall 1, above 65 the opening 12 in said front wall. These windows 18 are preferably of the "French" type, so as to be of an ornamental appearance. It will thus be seen that the entire

upper half of the front wall is made up of window construction providing a substantially transparent upper half for the wall. The side walls 2 of the compartment 6 are formed with "French" windows 20 in the 70 upper halves thereof.

By this arrangement, a great deal of light 75 is admitted to the operator's compartment 6, and provision is made for displaying the goods mounted in the compartment 7.

The food compartment 7 is divided into a plurality of package containing cells generally designated 21. These cells open into the compartment 6 and are adapted to contain goods to be sold and displayed so that 80 said goods will be visible from in front of, and outside the compartment 6. The cells 21 are preferably made up of a plurality of dispensing shelves 22 for round or cylindrical packages and shelves 23 for flat or irregularly shaped packages. I may divide the compartment 7 into sub-compartments by a partition 24 extending horizontally across the compartment approximately midway of the upper and lower ends thereof. 85 The shelves 22 for supporting cylindrical or round packages, such as canned goods, each comprise a pair of parallel tracks 25, said tracks being joined at their ends by cross bars 26 and secured in any suitable 90 manner within the compartments 6, but so as to be inclined downwardly towards the front or open side of the chamber 6. Each of the tracks 25 is provided with an inwardly laterally extending flange 27 which is in 95 turn formed with an upwardly extending flange 28. The cans or other objects to be dispensed ride upon the flanges 28 between the sides of the tracks so as to be prevented from rolling off of the tracks endwise. At 100 the forward ends of the tracks and between each pair, a concavo-convex receiver 29 is pivoted with its concave side uppermost. A pivot pin 30 extends across the tracks so as to pivotally support the receiver 29 and a 105 stop pin 31 disposed below the inner end of said receiver limits the movement of said receiver downwardly at its inner end. The forward end of the receiver is limited in its 110 downward movement by the forward cross bar 26. A plurality of cans or other objects to be dispensed is mounted upon the tracks of each shelf, such as cans of tomatoes, which are held therein by the receiver 29. I have shown the shelves 22 in the upper half 115 of the compartment 7 and the housing shelves in the lower half, but I may arrange these otherwise, as desired. Depending from the outer ends of the receivers 29 are suitable tags 32 which provide for designating 120 the goods in the particular shelf. When the foremost can rolls down on to the receiver, it passes over the inner portion of said receiver and raises the outer portion thereof 125 so as to form a stop. When the foremost 130

can is removed, the rear portion of the receiver drops to permit a succeeding can to roll upon it to take the place of the one which has been removed. Thus, it will be seen that at all times one can on each shelf is presented to view.

Referring to the shelves 23 for flat objects or packages, each shelf comprises tracks 33 suitably supported within the compartment 6 and adapted to in turn support flat packages such as the ones 34. The tracks 33 are mounted upon a frame 35 therefor, said frame including end pieces 36. Reciprocably mounted between the tracks of each shelf 15 and upon the end pieces 36 is an advancing bar 37. The upper surface of this bar normally lies below the upper surface 38 of the track upon which the packages rest but upon reciprocation of the bar, it will move into 20 engagement with the packages and tend to advance them along the tracks 33, as will later be more fully described. A retractile spring 39 is secured, as at 40, near one end of the bar 37, and as at 41, at its other end 25 to the end piece 36. This spring tends to return the bar to normal position after the bar has been pulled out by the operator. To provide for the raising of the bar when it is pulled outwardly, so that it will come into 30 contact with the packages and will advance said packages, I provide lugs 43 hinged, as at 44, to the rear end of the bar, and depending therefrom. These lugs are hinged so as to move forwardly only and to fold up 35 against the under side of the bar 37. The rear edges of the end pieces are beveled, as at 45. On the front end of the bar 37 there is provided a tab 46 depending therefrom. This tab is adapted to bear suitable characters to designate the particular commodity. 40 By grasping the tab 46 and pulling outwardly, the lugs 43 come into contact with the beveled faces 45 of the end pieces 36 and cause said bar to move upwardly and 45 engage the packages on the track. This will advance the packages into position to be readily removed from the shelf. The bars are pulled outwardly against the action of the springs 39 and when released, the 50 springs return the bars to normal position. As the bars begin to return to normal position, the lugs 43 fold up, and the bars immediately lower to their normal level, below that of the track supporting surfaces for the 55 packages. Thus, the bar tends to advance the packages only when it is pulled out.

The packages are arranged on the shelves 23 so that the foremost package on each shelf is in display position. It will thus be seen that I arrange the shelves in the compartment 6 so that practically the entire area 60 may be used for the goods to be displayed.

and sold. To insulate the compartments 6 and 7 from heat, I provide a dead air space 47 in the upper part of each compartment 65 by the use of false roof plates 48.

With reference to the foregoing description and the accompanying drawings, it will be seen that I have provided compact and an inexpensive apparatus which may be 70 readily set up to act as a store unit. As an example, the apparatus of this invention may be readily transported by truck to the point at which it is to be set up and in a very short time assembled for operation. 75 The goods to be displayed may be readily placed upon the shelves 22 by opening the back doors 48 and filling said shelves from the rear side of the structure. The shelves thus filled will dispose one commodity of 80 each kind in position to be viewed and by providing approximately the entire upper half of the operator's compartment of transparent walls, the entire device acts as a display cabinet and permits passers-by to 85 readily view the goods from in front of the operator's compartment 6. With the windows 18 closed, and the combined cabinet and counter 13 housed within the compartment 6, the apparatus presents a fanciful 90 store front appearance and is snug and weather-proof. By opening the windows 18 and extending the combined cabinet and counter 16, as shown in Figure 3 of the drawings, the apparatus is made ready for 95 use. The operator within the compartment 6 may readily remove the goods to be sold from the shelves and place them upon the counter 16.

I consider one of the most essential features of my invention to be the provision of an apparatus of a novel and inexpensive form, by means of which a miniature store or food station may be provided at various out-of-the-way and other points for the convenience of the consumers, and, in which the goods to be sold are at all times effectively displayed.

I claim:

In an apparatus of the character described, a compartment, open on one side thereof, a plurality of shelves mounted horizontally within said compartment, said shelves including tracks upon which commodities are adapted to rest, an advancing 110 bar mounted upon each shelf and normally disposed below the supporting surface of the tracks, and means for moving said bar above the supporting surface of the tracks when said bar is moved in one direction, and 115 for lowering said bars when moved in the other direction.

HENRY W. AENOLD.
